UNITED STATES PATENT OFFICE.

ALBERT HARRY WHEELER, OF WORCESTER, MASSACHUSETTS.

RECORD-BOOK.

1,126,165.

Specification of Letters Patent.

Patented Jan. 26, 1915.

Application filed December 28, 1907. Serial No. 408,368.

To all whom it may concern:

Be it known that I, ALBERT HARRY WHEELER, a citizen of the United States, residing at Worcester, in the county of 5 Worcester and State of Massachusetts, have invented a new and useful Record-Book, of which the following is a specification.

This invention relates to a record book which while capable of general use for keeping various kinds of records, is especially 10 adapted for keeping school or class records, and it will be described herein with special reference thereto.

One of the principal objects of this invention is to construct a record book of this character in such a way, that in addition to the usual column for names of the pupils and columns for the marks of their daily recitations or the like, there will be heads 15 for the latter columns in which entries may be made designating the lessons assigned each day so that when a pupil is absent, the instructor may tell from the record book alone just what lessons have been lost, as 20 well as those in which poor marks have been given.

Another object of the invention is to provide a construction in which the record may be extended so that a book of convenient 25 size may be employed for recording the necessary data for a large number of weeks or for a large number of pupils.

The invention embodies certain other improvements and advantages which will be 30 referred to hereinafter.

Reference is to be had to the accompanying drawing which shows a preferred form 35 of the invention and in which,

Figure 1 is a view in perspective of a record book embodying the features of the invention, and Fig. 2 is a plan of the same showing one way in which the leaves may be manipulated to extend the record, and showing the same modified by the omission 40 of the several headings and other data.

Referring particularly to the drawing, the example of the invention shown therein will now be described in detail.

In the first place, it will be obvious that 50 each sheet of the record book may consist of what may be called a single sheet or a double sheet; that is, it may be bound into the book at the edges or in the center so that in the latter case it will form two sheets 55 and in the former case, a single sheet. In both cases there will be a rear left hand

page designated in a general way by the letter *a* and a front right hand page designated by the letter *b*. These two pages together constitute a single record surface. 60 Each left-hand or rear page *a* is provided at a distance from its free end with a vertical line 10 extending from the top to the bottom of the page. This line defines and limits a left-hand column having at the top 65 thereof a space 11 which is preferably free from horizontal and vertical lines and which is provided with data indicating the subject matter of the record and preferably with a blank to be filled in. It may also be provided with a heading for the column below 70 which it is crossed by a series of horizontal rulings 12 which extend to the inner edge of the sheet and is designed, in the present form of the invention, to contain the names 75 of the pupils of a class or division. Above the horizontal rulings is a horizontal line 13 extending from the free edge of the left-hand page to the binding thereof and from the binding to the free edge of the right-hand page. This line 13 separates the part 80 of the sheet provided with the horizontal rulings 12 from the horizontal space above it which is designed to receive several kinds of headings as will be described hereinafter. 85 Extending below the line 13 and for a certain distance above it, are a plurality of heavy or dark vertical lines 14 which define a corresponding number of columns or sets 90 of columns on both pages. These columns are sub-divided by lighter vertical lines 15 into columns which are divided into spaces 16 by the horizontal rulings 12. These 95 spaces are designated to receive the daily markings or other data for which the record is designed. The light lines 15 extend above the line 13 to a horizontal line 17 which limits their upper ends. The lines 14 extend above the lines 17 to another horizontal line 18 above the line 17, forming horizontal 100 spaces 19 appropriately designed for receiving data indicative of the dates for which the columns between the lines 15 are to be used. It will be seen that on account of this construction a plurality of vertical heading 105 spaces 20 is provided, without horizontal rulings or cross lines. These spaces are designed to receive data indicative of the subject matter of each daily lesson or other record, and to be headed by the dates in the 110 spaces 19.

In order properly to designate these col-

umns, the first line 14 is spaced from the line 10 so as to form a column 21 at the head of which is a space 22 containing data indicative of the headings to be placed in 5 the heading columns 20, as for instance, the words "Daily lessons", which may be printed in if desired. In the column 21 below this heading may be placed the numbers of text-books loaned pupils or any 10 other data applying to the different pupils individually. Above the line 18 is another horizontal line 23 providing a horizontal space 24 containing data indicative of the months or years or both for which the record 15 is to be used and having a space 25 above it containing data indicative of the text-book to be used or other subject matter to correspond with the particular record to be kept.

20 The principles so far described are substantially the same on both the rear and front pages except that a space 26 on the front or right-hand page corresponding to the space 11 which has been described, is 25 provided with vertical lines 27 extending through the column below to the bottom of the page and dividing this space into columns 28 adapted to receive averages and having a heading indicating the same as for 30 example, the word "Averages."

It is to be observed that the line 13 extends across both pages at the same distance from the top and consequently that it appears twice on the same sheet at the front 35 and rear thereof, and it is also to be observed that the line 10 which appears on both pages is at the same distance from the free edge of the sheet in each case. In other words, the two lines 10 and the two ends of 40 the line 13 register with each other respectively. Now, in order to provide for extending this record to take in more time or more pupils or other subject matter, a strip 45 *c* between the vertical line 10 and the free edge of the sheet or the strip *d* between the horizontal line 13 and the top of the sheet may be removed along the line 10 or 13, as the case may be. To indicate this, data is provided along each of these lines as 50 indicated at 29 and 30 respectively, specifying that the strip *c* or *d* is to be removed along that line in order to extend the record in certain ways. Preferably also, in order 55 to facilitate this operation, these lines are provided with means whereby the strips *c* or *d* may be separated conveniently and easily along the lines. In the form of the invention shown in the drawings, this means consists of a series of perforations serving 60 in a well known manner to weaken the sheet along these lines for this purpose. It will be clear also, that as the lines on the sides of the sheet register with each other, these perforations may in themselves constitute 65 these lines and there need be no rulings

along them, although it is preferred to have both the perforations and rulings.

Now it will be seen that in case the columns between the vertical lines 14 represent weeks and it is desired to extend the record 70 for more than the number of weeks represented on a record surface of the book used, it will be an easy matter to tear off the strip *c* at the right of the line 10 on the right-hand or front page which of course will remove the space 11 and the column below it on the next page. It will be obvious that the names of the pupils or other subject matter of the record appearing in space 11 and the column below it brought to view by 75 removing the strip *c* will do for another record or for another part of the same record and this may be repeated indefinitely. For example, in case a book containing five columns between the lines 14 on each page 80 is to be used for a term of forty weeks it will be necessary to tear off three consecutive strips along the line 10 in order to extend the record for the whole period. Now it may be desired instead of extending the 85 record in this way, to extend it to contain the names of more pupils than could be placed in the column below the space 11. In order to do this, it is merely necessary to tear off the strip *d* as indicated in Fig. 2 90 along the line 13. In order to provide for conveniently doing this, the line 13 does not extend through the part of the sheet which is bound into the book but terminates in a vertical line 32 near said portion which 95 preferably is perforated like the line 13. In this way, the strip *d* can be removed and the additional data written on the next page as will clearly appear from Fig. 2.

It is to be observed that each of the lines 10 105 crosses the line 13 and that whether the strip *c* or *d* is removed, the space 11 must be removed in each case. In other words, the corner piece comprising the space 11 constitutes a part of the strip *c* and also a 110 part of the strip *d*. It is to be observed also that by the use of a record of this character, the entire class records for a term or year can be kept in a small compact book without necessitating the rewriting of the 115 headings, even if the term extends for a longer period than could be included on a single record surface. It is to be understood that this record is applicable to many uses beside school records but having illustrated 120 it as applied to a school record, I will now describe certain ways in which the same may be used for that purpose.

In order to keep a record for a class in which the number of names is not greater 125 than the number of spaces included in the column under the head "Names" and space 11 of one page and for any number of weeks not greater than the number of columns between the lines 14 of two pages, the names 130

are written in these spaces alphabetically or otherwise, as desired. The lessons assigned for each day in a particular subject may be entered by pages or paragraph numbers in the vertical leading spaces 20. By entering the days of the month over the vertical heading spaces, it will be seen that the scholarship marks recorded opposite the names of the individual pupils will appear each day in the same vertical column as the day of the month and the entry made for the lesson assigned for that particular day. By entering at convenient intervals in the spaces 20 chapter headings on the topics studied, it will be found that a chronological record of the progress of the class may be kept very easily for each subject studied.

By separating the strips *c* along the lines 10 according to the directions appearing 20 along said lines of the right-hand page, these pages can be narrowed to allow of extending the records of the class to include 20, 30, 40 or more weeks.

In order to keep a record for a class of 25 any number of names for the number of weeks provided for by a single record surface, as for instance, ten weeks or less, when the class contains more names than can be written in the column below the space 11, 30 the necessary number of leaves of the book may be torn along the line 13 and removed, in accordance with the instructions appearing. They are thus shortened so as to allow scholarship records to be kept for as many 35 names as may be desired for the period of ten weeks or any shorter period, according to the number of columns with which the particular book is constructed.

Whenever a pupil is absent, a horizontal 40 line may be drawn in the lower part of the space 16 assigned for his scholarship mark of that day and the record of the lesson to be made up for that day will be found in the space 20 at the head of that column. 45 When the lesson thus recorded is made up, the scholarship mark when entered will be found to be underlined and accordingly will be credited for the lesson made up. It will be seen, therefore, that the vertical spaces 20 50 are of much importance as they allow making an entry of the lesson assigned each day in line with the marks recorded for the recitations of the pupils, and when a pupil is absent the instructor may tell from the record without making any other entry therefor than the mark denoting absence, just what lesson has been lost and when it is made up, this also appears without any special entry. In addition to this, the subject 55 matter which may be incompletely learned by the pupils will appear at a glance on account of the markings being in the same columns with the headings indicating the subject matter. In other words, the record 60 book shows all the essential facts concerning

the recitation, including the lessons assigned each day and the way in which recitations have been made on those lessons, and although containing all of these matters, it is still of such a nature that it can be embodied in a small compact book for ordinary use and at small expense. 70

While I have illustrated and described a preferred form of the invention and at its application to the keeping of school records, 75 I am aware that the invention may be carried out in many other forms than that shown and that it may be applied with or without modifications to the keeping of various other forms of records without departing from the scope of this invention as expressed in the claims. Therefore, I do not wish to be limited to the details of construction form and arrangement which have been described above nor to the application of 80 the invention to any particular kind of record, but

What I do claim is:—

1. A record book comprising a series of sheets bound together each having a vertical 90 line at a distance from the outer free edge thereof, said line being represented on both sides of the sheet and having on the front page thereof data indicating that the sheet is to be separated along that line to extend 95 the record to cover more than a certain amount of matter, said lines defining and limiting columns on both sides of the sheet, said sheet also having a horizontal line spaced from the top thereof and crossing 100 said vertical line, said horizontal line extending from the outer free edge to a point near the inner bound edge of the sheet and having a vertical line extending from its 105 inner end to the top of the sheet, said last 110 named horizontal and vertical line being represented on both sides of the sheet and having data on one page indicating that the page is to be torn off along this line to extend the record.

2. A record book comprising a series of sheets bound together each having a vertical line at a distance from the outer free edge thereof, said line being represented on both sides of the sheet and having on the 115 front page thereof data indicating that the sheet is to be separated along that line to extend the record to cover more than a certain amount of matter, said lines defining and limiting columns on both sides of the 120 sheet, said sheet also having a horizontal line spaced from the top thereof and crossing said vertical line, said horizontal line extending from the outer free edge to a point near the inner bound edge of the sheet 125 and having a vertical line extending from its inner end to the top of the sheet, said last named horizontal and vertical line being represented on both sides of the sheet 130 and having data on one page indicating that

the page is to be torn off along this line to extend the record, the sheet having a column heading space at the outer upper corner adapted to be separated from the sheet 5 whenever the same is separated along either of said lines, the sheet containing on both sides thereof between said vertical lines and the bound edge of the sheet a series of vertical lines dividing the respective pages into 10 columns, said sheet having horizontal rulings below said horizontal line crossing all of said lines and columns on both sides, and having column heading spaces above the horizontal line on both pages free from 15 horizontal cross rulings and defined by said lines.

3. A record book comprising a series of sheets bound together each having a weakened vertical line at a distance from the 20 outer free edge thereof, said line being represented on both sides of the sheet, said lines defining and limiting columns on both sides of the sheet, said sheet also having a weakened horizontal line spaced from the 25 top thereof and crossing said vertical line, said horizontal line extending from the outer free edge to a point near the inner bound edge of the sheet and having a weakened vertical line extending from its inner 30 end to the top of the sheet, said last named horizontal and vertical line being represented on both sides of the sheet, the sheet containing on both sides thereof between said vertical lines and the bound edge of 35 the sheet a series of vertical lines dividing the respective pages into columns, said sheet having horizontal rulings below said horizontal line crossing all of said lines and columns on both sides, and having column 40 heading spaces above the horizontal line on both pages free from horizontal cross rulings and defined by said lines, and a space at the left of said heading spaces on the left-hand or rear page containing data indicative 45 of the headings to be placed in said heading spaces for the respective columns, whereby said space constitutes a heading for all the heading spaces on the rear page on which said space is located and on the next 50 following front or right hand page.

4. A record book comprising a series of sheets bound together at the inner edges of their pages and each having a weakened vertical line on both sides of the sheet, a 55 weakened horizontal line on both sides of the sheet crossing the vertical line and spaced from the top, horizontal rulings in the space below the horizontal line on both sides of the sheet, and vertical rulings in 60 the space between the vertical line and the binding edge of the sheet and below the horizontal line on both sides of the sheet, certain of said vertical rulings extending a distance above the horizontal line to form 65 heading spaces free from horizontal cross

rulings and having spaces above them, a space at one side of said spaces without cross rulings having data indicative of the headings to be placed therein, said last named data constituting a heading for the 70 spaces of two consecutive pages formed on said sheets.

5. A record book comprising a series of sheets bound together, each having a vertical line on each side thereof spaced from the free edge, data along said line indicating that the sheet is to be separated along said line to extend the record, horizontal and vertical rulings on both sides of the sheet in the spaces between said vertical lines and the binding, said horizontal rulings extending into the spaces between the vertical lines and the free edge of the sheet, vertical lines forming columns in the space beyond the first named vertical line on the 85 front or right-hand page, a horizontal line spaced from the top of the sheet on both sides, said first named vertical lines extending above said horizontal line on both sides of the sheet, all of said horizontal rulings 90 being located below said horizontal line whereby spaces are constituted above the horizontal line, said last named spaces having a designation at the side thereof for indicating headings to be placed therein and 95 being free from cross rulings.

6. A record book comprising a series of sheets bound together along a vertical line, whereby each rear or left-hand page and the following front or right-hand page may 100 constitute an entire record surface, each sheet having a vertical line on each side at substantially the same distance from its free edge, said lines defining two vertical columns, one on the front right-hand page 105 sub-divided by lines into vertical columns, data located along said line of each right-hand page indicating that the paper is to be separated along that line to extend the record to cover a longer period than that 110 for which a single record surface is designed, each sheet also being provided with a horizontal line at a distance from the top 115 extending across both sides to a point near that at which the sheets are bound together and from that point extending vertically therefrom to the top of the sheet, said horizontal line crossing said first named vertical lines and extending to the free edge of the sheet, the portion of said sheet located 120 inside or between the two first mentioned vertical lines being provided with a series of vertical lines dividing the same into a number of columns, said columns extending above and below the said horizontal line and having above said horizontal line a series of heading spaces without horizontal cross rulings, extending from one of said first named vertical lines on the left-hand page substantially 125 to the corresponding vertical line on 130

the next right-hand page and having at the left-half thereof a space containing data indicative of subject matter to be placed in said heading spaces.

- 5 7. A record book comprising a series of sheets bound together each having a vertical line at a distance from the outer free edge thereof, said line being represented on both sides of the sheet and having on the front 10 page thereof data indicating that the sheet is to be separated along that line to extend the record to cover more than a certain amount of matter, said lines defining and limiting columns on both sides of the sheet, 15 said sheet also having a horizontal line spaced from the top thereof and crossing said vertical line, said horizontal line extending from the outer free edge to a point near the inner bound edge of the sheet and 20 having a vertical line extending from its inner end to the top of the sheet, said last named horizontal and vertical line being represented on both sides of the sheet and having data on one page indicating that the 25 page is to be torn off along this line to extend the record, the sheet having a column heading space at the outer upper corner adapted to be separated from the sheet whenever the same is separated along either 30 of said lines, the sheet containing on both sides thereof between said vertical lines and the bound edge of the sheet a series of vertical lines dividing the respective pages into columns, said sheet having horizontal rul- 35 ings below said horizontal line crossing all of said lines and columns on both sides, and having column heading spaces above the horizontal line on both pages free from horizontal cross rulings and defined by said 40 lines, and a space at the left of said heading spaces on the left-hand or rear page containing data indicative of the headings to be placed in said heading spaces for the respective columns, whereby said space con- 45 stitutes a heading for all the heading spaces on the rear page on which said space is located and on the next following front or right hand page.

8. A record book comprising a series of 50 sheets bound together, each having a vertical line on each side thereof spaced from the free edge, data along said line on one side of the sheet indicating that the sheet is to be separated along said line to extend 55 the record, horizontal and vertical rulings on both sides of the sheet in the regions between said vertical line and the binding edge, said horizontal rulings extending into

the spaces between the vertical line and the free edge of the sheet, and a horizontal line 60 along each page near the top, above which the vertical rulings extend and along which horizontal line the top of the leaf can be separated from the rest of the sheet.

9. A record book comprising a series of 65 sheets bound together and each provided with perforations therethrough, said perforations being located in a horizontal line spaced from the top of the sheet and in a vertical line from the inner end 70 of said horizontal line to the top of the sheet, whereby the upper part of said sheet may be separated along said horizontal and vertical lines without tearing or injuring the binding of the book, and horizontal and 75 vertical rulings on both sides of the sheet in the spaces between said vertical line and the binding edge, said horizontal rulings extending into the spaces between said vertical line and the free edge of the sheet. 80

10. A record book comprising a series of sheets bound together and each provided with perforations therethrough, said perforations being located in a horizontal line spaced from the top of the sheet extending 85 from the free edge thereof close to the binding and in a vertical line from the inner end of said horizontal line to the top of the sheet close to the binding, whereby the upper part of said sheet may be separated along said 90 horizontal and vertical lines without tearing or injuring the binding of the book.

11. A record book comprising a series of sheets bound together, each having a vertical line on each side thereof extending 95 from the top to the bottom thereof, data along said line on the side of the sheet indicating that the sheet is to be separated along said line to extend the record, horizontal and vertical rulings on both sides of the sheet 100 in the regions between said vertical line and the binding edge, said horizontal rulings extending into the spaces between the vertical line and the free edge of the sheet, and a horizontal line along each page near the top, 105 extending substantially across the entire width of the sheet and along which horizontal line the top of the leaf can be separated from the rest of the sheet.

In testimony whereof I have hereunto set 110 my hand, in the presence of two subscribing witnesses.

ALBERT HARRY WHEELER.
